(57) **CLAIM**

The ornamental design for a climbing apparatus, as shown and described.

DESCRIPTION

FIG. 1 is a left side front perspective view of a climbing apparatus in accordance with my new design.

FIG. 2 is a front elevational view thereof.

FIG. 3 is a rear elevational view thereof.

FIG. 4 is a left side elevational view thereof.

FIG. 5 is a right side elevational view.

FIG. 6 is a top elevational view thereof.

FIG. 7 is a bottom elevational view thereof.

FIG. 8 is a left side front perspective view of the A-frame ladder element of the climbing apparatus of FIG. 1.

FIG. 9 is a front elevational view of FIG. 8.

FIG. 10 is a rear elevational view of FIG. 8.

FIG. 11 is a left side elevational view of FIG. 8.

FIG. 12 is a right side elevational view of FIG. 8.

FIG. 13 is a top elevational view of FIG. 8.

FIG. 14 is a bottom elevational view of FIG. 8.

FIG. 15 is a left side front perspective view of the bridge element of the climbing apparatus of FIG. 1.

FIG. 16 is a front elevational view of FIG. 15.

FIG. 17 is a rear elevational view of FIG. 15.

FIG. 18 is a left side devotional view of FIG. 15.

FIG. 19 is a right side devotional view of FIG. 15.

FIG. 20 is a top elevational view of FIG. 15.

FIG. 21 is a bottom elevational view of FIG. 15.

FIG. 22 is a left side front perspective view of the arched ladder element of the climbing apparatus of FIG. 1.

FIG. 23 is a front elevational view of FIG. 22.

FIG. 24 is a rear elevational view of FIG. 22.

FIG. 25 is a left side devotional view of FIG. 22.

FIG. 26 is a right side devotional view of FIG. 22.

FIG. 27 is a top elevational view of FIG. 22; and,

FIG. 28 is a bottom elevational view of FIG. 22.
